UNITED STATES PATENT OFFICE.

ELI J. BLAKE, OF WESTFIELD, NEW JERSEY, ASSIGNOR TO HALL SWITCH & SIGNAL CO., A CORPORATION OF MAINE.

TRAIN-CONTROL SYSTEM.

Application filed January 11, 1917. Serial No. 141,816.

To all whom it may concern:

Be it known that I, ELI J. BLAKE, a citizen of the United States, and a resident of the town of Westfield, county of Union, and 5 State of New Jersey, have invented certain new and useful Improvements in Train-Control Systems, of which the following is a specification.

It has heretofore been customary to locate 10 roadside signals at intervals not less than the braking distance of the fastest trains. A stop signal has been displayed at the entrance to each occupied block, a caution signal at the entrance to the next block in the 15 rear and a proceed signal at the entrance to the second block in the rear. Between each train and the next proceed indication in the rear there has thus been maintained a distance composed of: first, the distance be- 20 tween the train and the entrance to the block which it occupies; second, the distance between the stop signal and the caution signal, which must not be less than the maximum distance required to stop a train; and, 25 third, the distance between the caution signal and the next signal in the rear. Of these three distances only the second is dictated by safety; the first and third are due to the spacing of signals along the roadway.

In order to reduce the interval between 30 trains, and thereby increase the traffic capacity of the railway, the length of blocks has sometimes been made only half of the maximum braking distance. Two dis- 35 tinctive caution signals have then been displayed in the rear of the entrance to the occupied block, so that the total length of the second, or caution zone, remains the same as in the first instance; but the length of 40 the first and third zones is reduced. This is the well known system of block signaling with one block overlap.

It is evident that further subdivision of 45 the blocks with multiple blocks overlap would permit the first and third zones to be made very small so that the headway between trains operating on proceed, or full speed, signals could closely approach the minimum distance dictated by safety, which is the maximum distance required for stopping the following train. Furthermore, by the use of distinctive caution signals, indicating the number of clear blocks between each signal and the occupied block, operation at restricted speeds could be permitted

at correspondingly reduced headway. But the expense incident to installing a large number of signals, each arranged to give several distinct indications, together with the necessary line wires and controlling devices, has hitherto limited the application of this system to comparatively few cases, and in those cases to comparatively large subdivisions of the usual length of blocks.

One object of my invention is to provide 60 a practicable system of overlapping control for signals in accordance with the principles that have been discussed, without the use of line wires extending through the control zones of the signals, and thereby to permit 65 of safely operating trains at reduced headway.

Another object is to reduce the number of 70 signals required for overlapping control, and at the same time to insure the visibility 75 of signals under all conditions, by substituting cab signals for roadside signals.

Another object is to provide means for automatically controlling the train in accordance with the indications of the signals if 80 the engineman fails to do so; which means will not act so long as the engineman is governed by the signals.

Another object of my invention is to provide 85 on the train continuous indications of the condition of the track in advance, which indication will be predisposed to indicate danger, every safety indication being dependent on the integrity of track circuits and all other parts of the system in accord- 90 ance with the best signaling practice.

Another object is to provide for safely 95 operating trains at various speeds, the minimum headway between trains being dependent on the speed of the following train, and approximating the distance required to bring it to rest from the speed at which it is moving.

Another object is to permit the movement 100 of the maximum possible traffic over the railroad without permitting any train to approach a dangerous point at a speed which would prevent stopping short of the danger point.

Another object is to provide controlling 105 apparatus and circuits which will attain the ends that have been enumerated with minimum of apparatus and of conductors.

Another object is to provide means on the 110 train whereby its operation under given

conditions can be limited to a definite speed. The means by which I attain these and other objects are shown in the accompanying drawings and described in the following specification.

Fig. 1 is a diagrammatic plan view of a portion of a railway equipped with my invention and showing one means by which signals can be given on the train and observance of the same can be enforced by automatic apparatus on the train.

Figure 2 shows a form of frequency indicator that may be used in place of color light indications.

Figure 3 shows a combination of two frequency relays of any type arranged to give the same result as the selective relay shown in Figure 12.

Figure 4 shows a modification of the system arranged to control a roadside signal instead of a signal on the train.

Figure 5 shows a modification of the system.

Figures 6 to 10 inclusive show modifications of the apparatus carried by the train for controlling it.

Figure 11 shows a timing device by which under certain conditions the speed of the train may be limited.

Figure 12 shows a relay designed to close one of several circuits selectively in accordance with the frequency by which the relay is energized.

Referring first to Figure 1. 1 and 2 are the rails of one railway track, divided by insulated joints 3 in the block sections *a*, *b*, *c*, *d*, *e*. 4, 5 and 6 are three conductors extending along the track. Between each two of these conductors is maintained by any suitable means, an alternating difference of potential. From conductor 4 to conductor 5 this potential has one frequency, and from conductor 5 to conductor 6 another frequency; and from conductor 6 to conductor 4 a third frequency. Connected in shunt across the lines 4, 5 and 6 near the entrance end of the block *a* are connected the primary windings of the three transformers 7^b, 8^b and 9^b, each energized at a different frequency. One secondary terminal of each transformer is connected to the rail 1 near the exit end of the block section *b*. The other terminal of one or another of the three transformers is connected selectively to a corresponding point in the rail 2 through a relay contact 10^a. The selection of contact points in this relay is determined by the frequency of current supplied to its operating winding 11^a or the absence of such current, as hereafter described. The winding 11^a receives its energy as shown from the rails at the rear end of block *a*. Similar apparatus and connections are employed at the corresponding point of each block section. Thus there will be supplied to block section *c* at its exit end a cur-

rent of some frequency from a transformer not shown. I have indicated at 12, a pair of wheels across the rails in block section *a*, furnishing a shunt path of low resistance and practically preventing the flow of any current through the relay winding 11^a.

Under this condition the relay contact is closed as shown to the secondary terminal of transformer 9^b and the block section *b* is supplied with current of the frequency supplied by the lines 4 and 6. The relay 11^b at the rear end of this block (which is unoccupied), is therefore, energized at the same frequency, with the result that the contact 10^b is raised to the position shown and the following block *c* is supplied with energy of the frequency of the lines 4 and 5. The block *c* being also unoccupied the relay winding 11^b is supplied with energy at the last named frequency with the result that the contact 10^c assumes the position indicated, causing energy of the frequency of the lines 5, 6 to flow into the block *d*.

The relay winding 11^c at the rear end of the block *d* is energized at the frequency of the lines 5, 6. The contact 10^d is arranged to assume at this frequency, the same position which it assumes at the frequency of the lines 4, 5 so that same frequency is supplied to the block *e* in the rear, and in the same manner to succeeding blocks.

It will thus be seen that energy is supplied to successive clear block sections in the rear of any occupied block as follows:

To the first block at the frequency of the lines 4, 5; to the second block at the frequency of the lines 4, 5; to the third and to all succeeding unoccupied blocks at the frequency of the lines 5, 6. Evidently there has thus been provided a distinctive indication in each block of the number of clear blocks in advance up to two blocks which indications can be received by any device capable of responding selectively to the three frequencies in question. For example I have indicated at 13 in the block *e* a pair of wheels and an axle constituting the primary winding of a transformer 14 carried by a following train. From the secondary winding of this transformer current is taken to an amplifying device 15 which also receives energy from a battery 16, any known type of amplifier may be used, for example the audion type or that shown in my application Serial No. 135,120. Amplified current from the amplifying device 15 flows through the winding 16^a of a relay similar to the relays 10. Since the amplified current has the same frequency as the current in the rails from which it is derived the contact 17 of this relay will close selectively a circuit through the lamps G, Y or R, or will open all of these circuits according as energy at one or another frequency or no energy, is received from the rails.

The current from the lamps G Y or R if any, passes also through a speed controlling device 18 and thence through a magnet 19 controlling the application of the brakes on 5 the train, or through a wire 20 as the case may be, to the battery 16. The speed controlling device 18 which may consist of one or more devices as shown in Figure 11, or any other suitable speed control device is 10 so arranged as to close the circuit through magnet 19 when the speed of the train is within the limits permissible under the indication received from the track corresponding respectively to the lamp G Y or 15 R; but to complete this circuit through the wire 20 without passing through the magnet 19 whenever the speed exceeds the value permissible under the given conditions. That is to say, contact 27^G—36^G is closed 20 at all speeds at and below a given high value, and at speeds exceeding such value this contact opens and contact 27^G—20^G closes, so that when the circuit through lamp G is closed at contact 17, brake magnet 19 is energized 25 when the speed is at or below the given high value and de-energized when the speed exceeds such given high value. Similarly, contact 27^Y—36^Y is closed at all speeds at and below a given intermediate value, 30 whereas at speeds exceeding such value this contact opens and contact 27^Y—20^Y closes, so that when the circuit through lamp Y is closed at contact 17, brake magnet 19 is energized or de-energized according as the 35 speed is below or above such intermediate value. Also, contact 27^R—36^R is closed at all speeds at and below a given low value, whereas at speeds exceeding such value this contact is open and contact 27^R—20^R is 40 closed, so that when the circuit through lamp R is closed at contact 17, brake magnet 19 is energized or de-energized according as the speed is below or above such given low value. Each group of contacts 45 27—36—30 may be controlled by a device similar to that shown in Fig. 11 described hereinafter. The magnet 19 controls a valve 70 arranged to set the brakes when the magnet is de-energized.

In Figure 1 it is evident that in addition to the direct path through the generator connected directly to any given pair of conductors there is a second path through the other two generators in series. In order to 55 avoid short circuiting of one armature by the path through the other two armatures and also in order to avoid the supply to any given pair of conductors of any considerable current other than that of the alternator directly connected across them, each alternator or its circuit, should have the characteristic of permitting freely the flow of current at its proper frequency and practically preventing the flow of current at the 60 frequencies of the other generators. It is

well known in the art that this condition can be obtained by a proper balance of inductance and condensance 71 in each circuit.

Referring now to Figure 5, in this figure 70 I show circuits similar to those of Figure 1 with the following exceptions: The insulated joints which separate the track rails between adjacent block sections are bridged by inductive bonds 21 of the well known 75 balanced type, for the purpose of carrying the return current of an electric traction system. The same circuit is used as a common return for the circuits of the three alternators 22, 23 and 24, while each of the 80 conductors 4, 5 and 6 is connected only to one alternator. In instance the three frequencies are obtained by the use of one conductor for each frequency in addition to the common return path through the rails connection to 85 the latter path is made at the neutral points of the balanced bonds.

While I have shown in Figures 1 and 5 arrangements for the use of only three frequencies for controlling traffic over a corresponding number of blocks in the rear of each occupied block, it is evident that the same principles can be applied with the use of any number of frequencies to control traffic over any number of blocks in the rear of 90 the occupied block, and although I have shown only two types of track circuits, the same principles can be applied with any type of track circuit which will permit the energy supply to one block to be made 95 dependent on the energy supplied to the next block in advance. It is also evident that the indications given by the selection of the frequencies may be used for other purposes than the indication of clear blocks ahead as 100 for example, for indicating routes through interlocking plants.

In Figure 4 I have shown another form of my invention in which supply of current to the various blocks is identical with that 110 shown in Figure 1, but the current is used to select the indication given by roadside signal 25. In this instance the relay has in addition to the contact arm 10^a, etc., required for supplying current to the block in 115 the rear a second contact arm 26^a, etc., moving in the same manner as the arm 10^a, etc., but employed to supply current selectively to one or another lamp of the light signal 25.

Figures 6, 7, 8, 9, and 10 show various arrangements of apparatus on the train which may be used in place of the lamps and speed control device shown in Figure 1. In each case the devices shown are controlled by the current delivered by the amplifier 15 in 120 Figure 1.

In Figure 6 I have shown an arrangement of relay-controlled circuits on the train by means of which one or another of three signal lamps G Y and R, is illuminated, ac- 125

cording to the number of clear blocks in advance of the train.

In Figure 2 I have shown in place of the relay and lamps of Figure 6 a frequency indicator of the type in which a pointer swings across a scale as the frequency rises. But instead of graduation indicating frequency supplied to the meter I have shown graduation indicating for each frequency the number of clear blocks ahead.

In Figure 7 I have shown the same circuit as in Figure 6 with the addition of a magnet 19 for controlling application of the brakes and a speed control device 27 such as shown in Figure 11, having the characteristics of opening an electrical circuit when the speed exceeds a certain value. The speed at which the circuit through the speed control device 27 will open is determined by the distance traveled by the train in such a manner as to bring the train to rest substantially at the exit end of the block in which this circuit was first energized irrespective of the speed at which the train entered the block.

It will be evident by examination of Figure 7 that as long as the lamp G is energized, indicating three clear blocks in advance of the train, the magnet 19 will be energized. This magnet is associated with the air brake system in such a manner that releasing the magnet will cause the brakes to be applied. Upon entering the second clear block in the rear of an occupied block the frequency supplied to the train will be changed to that fed to the second clear block in the rear and the contact arm 17 will drop to the position in which the battery circuit is closed through the lamp Y the speed control device 27, and the magnet 19. The magnet 19 will now remain energized as long as the train does not exceed at any point the maximum speed which will permit of its being stopped at the exit end of the block in which it is traveling. On reaching the first clear block in the rear of the occupied block the contact arm 17 will close the circuit through the lamp R and open the circuit through the magnet 19, causing the train to stop immediately.

In Fig. 8 I have shown circuits controlled by a relay operating in four positions, each corresponding to a particular frequency and a corresponding number of clear blocks in advance of the train, and a fifth position corresponding to absence of energy. In this instance the lamp G, indicating full speed, is lit as long as there are three clear blocks in advance of the train. A first caution indication is given by the lamp Y three blocks in the rear of the occupied block. As long as current flows through either the lamp G or the lamp Y the magnet 19 remains energized, but upon entering the second clear block, in the rear of the occupied block contact 17 is closed through the lamp B, the

contact 27^b and the magnet 19, the contact 27^b as described hereafter is arranged to open whenever the train exceeds a definite speed limit. Similarly the circuit through the lamp R is closed through the contact 27^r, corresponding to a lower speed limit, and the magnet 19. As the train approaches an occupied block, it receives first a yellow light warning the engineer to reduce his speed to the limit corresponding to the contact 27^b. Should he fail to do so the brakes will automatically be applied at the entrance of the second clear block in the rear of the occupied block. At the same point, irrespective of speed, the lamp B is lit, indicating that speed must be reduced before entering the next block to the value corresponding to the contact 27^r. The latter contact is adjusted for a low speed at which it is permissible to operate the train all the way to the entrance of the occupied block; but upon reaching the latter point the relay contact arm 17 will open the circuit of the magnet 19 and cause the automatic application of the brakes.

In Figure 9 I have shown an arrangement similar to Figure 8, with the exception that the speed which will cause an automatic application of the brakes instead of being constant for each block diminishes as the block is traversed. This result is obtained by including in the circuits of the lamps Y B and R speed limiting devices similar to 27 in Figure 7. In each case the speed limit device 27 is adjusted to enforce a speed limit varying between the permissible limits at the entrance and exit ends of the block.

In Figure 10 I have shown an arrangement similar to Figure 7 except that two speed control devices 27^H and 27^L are here employed in place of the single device 27 in Figure 7. However, only one of these devices acts at any given location. The train is controlled by track circuits of three frequencies in the rear of the occupied block as in the case of Figure 7; but at different locations two different frequencies are supplied to the second clear block in the rear of the occupied block; one frequency adapted to select the speed control devices 26^H while the other frequency is adapted to select the speed control devices 26^L, for controlling the train in a different manner. For example, the first frequency may be employed on level tracks and the second on down grades, and the control devices 26^H and 26^L may be adjusted for corresponding braking curves. Similarly speed control in accordance with one of any number of braking curves can be selected by the use of suitable controlling devices, responsive to different frequencies.

In Figure 11 I have shown one form of speed controlled contact device suitable for enforcing a constant speed limit. A cam 30 is mounted on a shaft 31, which is driven, by

gearing or otherwise, at a speed proportioned to the speed of an axle of a train. Resting upon the cam 30 is a roller 32 carried by a heavy arm 33, loosely mounted at 34 on the 5 extended shaft of a clock or other timing mechanism 35. The timing mechanism 35 is so arranged that the shaft 34 may be turned counter clockwise against the torsion of the mainspring without other restriction; but 10 clockwise movement is limited to a definite maximum rate. Rigidly attached to the shaft 34 is a sector ratchet 29 carrying an insulated arm 28. The latter arm is arranged under normal running conditions to move 15 upward with each revolution of cam 30 almost into engagement with the contact finger 27 which rests upon a fixed contact member 36 and closes a control circuit between the wires 37 and 38. A pawl 39 on the arm 33 20 normally engages the second notch 40 of the sector ratchet 29 as indicated. As long as the permissible speed of the train is not exceeded the arm 33 oscillates in unison with the ratchet 29 during each revolution of the 25 cam 30, carrying the ratchet 29 and the arm 28 to the position indicated, without opening the contact between the parts 27 and 36. During the following revolution, the arm 33 gradually rises to its highest position and the 30 arm 28 drops away from the contact finger 27. The sector ratchet 29 continues to engage the pawl 39, at second notch. However, should the speed of the train be such that the upward movement of the arm 33 is more 35 rapid than the maximum speed at which the timing mechanism 35 will permit the sector ratchet 29 to revolve, then the arm 33 will carry the pawl 39 to the first notch 41 of the sector ratchet 29. The succeeding downward 40 movement of the arm 33 will raise the arm 28 to the position shown in broken lines and cause the contact between the fingers 27 and 36 to be broken. At the same time a pawl 42 pivoted on the case of the timing mechanism 45 45 will engage the third tooth 43 of the sector ratchet 29, causing the contacts 27 and 36 to remain open until the pawl 42 has been released.

In Figure 12 I have shown a relay designed to respond selectively to various frequencies. A single phase induction motor 44 having an extended vertical shaft 45 carries two centrifugal governors 46 and 47. The former is arranged to fly out at a certain speed of revolution corresponding to a certain frequency current at the motor 44. In so doing, it will raise the collar and sleeve 48, on which the governor 47 is carried, through a small distance. At another and higher speed the weights of governor 47 will fly out raising the sleeve 49. The tip of the sleeve 49 may thus occupy three different positions, the lowest when the speed is insufficient to throw out either of the governors 50 55 60 65 46 and 47; the intermediate position when 46

is thrown out and 47 is not thrown out; and the highest position when both are thrown out. Resting upon the tip of the sleeve 49 is a plate 50 attached to and insulated at 51 from the contact arm 52. The latter through a spring contact tip 53 closes the circuit between the wire 54 and the wires 55, 56 and 57, according as the sleeve 49 occupies one or another of the positions which have been described, hence according as the motor 44 is energized by current of one or another frequency.

In Figure 3 I have shown symbolically an arrangement of two relays of the well known frequency selective type, one relay 58 arranged to close only when the frequency supplied to it is less than a certain value, the other relay 59 arranged to close only when the frequency supplied to it exceeds another and higher value. It is evident from inspection that the circuit from the wire 54 to the wires 55, 56 and 57 will here be made selectively as in the case of the relay last described.

While I have shown and described certain specific embodiments of my invention, I do not wish to limit myself to these specific embodiments. It will be evident to anyone skilled in the art that the principles here described can be employed in many other ways and to give many other indications than those I have described.

Furthermore, while I have described primarily a system in which the indications given at the train or at the roadside are dependent automatically on the condition of track in advance, in accordance with automatic block signaling practice, it is evident that the same principles can be applied for giving indications of any desired conditions, as in the case of interlocking signals.

Having described my invention, what I claim as new and desire to secure by Letters Patent is:

1. A railway signaling system comprising a trackway; means for dividing the trackway into signaling sections; means for supplying to each signaling section a plurality of alternating current potentials of different frequencies; devices associated with each signaling section for controlling the frequency to be supplied to the adjacent section and controlled as to its operation by the passage of a vehicle along the trackway; a vehicle for travel along the railway; a circuit on the vehicle arranged to receive energy from the alternating potential of the signaling section on which it may be located; an amplifying means on the vehicle and included in said circuit; an electrically operated device which is selectively controlled by the operation of the amplifying means; and a plurality of governing means on the vehicle which are selectively controlled by said electrically operated device.

2. A railway signaling system comprising a trackway; means for dividing the trackway into signaling sections; means for supplying to each signaling section a plurality of alternating current potentials of different frequencies; devices associated with each signaling section for controlling the frequency to be supplied to the adjacent section and controlled as to its operation by the passage of a vehicle along the trackway; a vehicle for travel along the railway; a circuit on the vehicle arranged to receive energy from the alternating potential of the signaling section on which it may be located; an amplifying means on the vehicle and included in said circuit; an electrically operated device which is selectively controlled by the operation of the amplifying means; and a plurality of signals on the vehicle which are selectively controlled by said electrically operated device.

3. A railway signaling system comprising a trackway; means for dividing the trackway into signaling sections; means for supplying to each signaling section a plurality of alternating current potentials of different frequencies; devices associated with each signaling section for controlling the frequency to be supplied to the adjacent section and controlled as to its operation by the passage of a vehicle along the trackway; a vehicle for travel along the railway; a circuit on the vehicle arranged to receive energy from the alternating potential of the signaling section on which it may be located; an amplifying means on the vehicle and included in said circuit; an electrically operated device which is selectively controlled by the operation of the amplifying means; signals on the vehicle which are selectively controlled by said electrically operated device; and a brake controlling magnet in circuit with one of said signals.

4. A railway signaling system comprising a trackway; means for dividing the trackway into signaling sections; means for supplying to each signaling section a plurality of alternating current potentials of different frequencies; devices associated with each signaling section for controlling the frequency to be supplied to the adjacent section and controlled as to its operation by the passage of a vehicle along the trackway; a vehicle for travel along the railway; a circuit on the vehicle arranged to receive energy from the alternating potential of the signaling section on which it may be located; an amplifying means on the vehicle and included in said circuit; an electrically operated device which is selectively controlled by the operation of the amplifying means; signals on the vehicle which are selectively controlled by said electrically operated device; a brake controlling magnet in circuit with one of said signals; and a speed con-

trol device in circuit with another of said signals and said brake controlling magnet.

5. A railway signaling system comprising a trackway; means for dividing the trackway into signaling sections; means for supplying to each signaling section a plurality of current potentials of different cyclic variations; devices associated with each signaling section for controlling the current to be supplied to the adjacent section and controlled as to its operation by the passage of a vehicle along the trackway; a vehicle for travel along the trackway; a circuit on the vehicle adapted to receive energy from the signaling section on which the vehicle may be located, and speed control apparatus on the vehicle selectively responsive to the electric currents of different cyclic variations, and including one member moving at constant speed and another member coacting therewith and moving at a speed dependent upon the speed of the train.

6. A railway signaling system comprising a trackway; means for dividing the trackway into signaling sections; means for supplying to each signaling section a plurality of alternating current potentials of different frequencies, a device associated with each signaling section for controlling the frequency to be supplied to the adjacent section and controlled as to their operation by the passage of a vehicle along the trackway; a vehicle for travel along the railway; a circuit on the vehicle arranged to receive energy from the alternating potential of the signaling section on which it may be located; and control apparatus on said vehicle comprising an alternating current motor revolving at a speed dependent upon the frequency of current received from the track to control one or more circuits on the train.

7. A train control system comprising a trackway; means for dividing the trackway into signaling sections, means comprising an alternating current motor revolving at a speed dependent upon the frequency of the current supplied to the motor to control contacts to selectively supply energy of one or another frequency to the signaling sections; a vehicle for travel along the trackway, and control apparatus on said vehicle selectively responsive to the electric power of different frequencies in the track.

8. A railway signaling system comprising a trackway; means for dividing the trackway into signaling sections; means for supplying to each signaling section a plurality of alternating current potentials of different frequencies; devices associated with each signaling section for controlling the frequency to be supplied to the adjacent section and controlled as to its operation by the passage of a vehicle along the trackway; a vehicle for travel along the

- railway; a circuit on the vehicle arranged to receive energy from the alternating potential of the signaling section on which it may be located; an electrically operated 5 device selectively controlled according to the frequency of the potential supplied to said circuit; and an amplifying means interposed between said circuit and said device.
- 10 9. A railway signaling system comprising a trackway, means for dividing the trackway into signaling sections; means for supplying to each signaling section a plurality of current potentials of different 15 cyclic variations; devices associated with each signaling section for controlling the current to be supplied to the adjacent section and controlled as to its operation by the passage of a vehicle along the track- 20 way; a vehicle for travel along the trackway; a circuit on the vehicle adapted to receive energy from the signaling section on which the vehicle may be located; amplifying means in said circuit, and apparatus selectively responsive to the electric 25 currents having different cyclic variations.
10. Railway traffic controlling apparatus comprising a series of track sections, means for each section for connecting a source of 30 alternating current of one frequency or another across the rails of the section at the exit end of the section according to traffic conditions in advance of the section, a circuit on a train receiving voltage from the 35 track rails by induction, governing means on the train controlled by the voltage induced in said circuit and including means selectively responsive to currents of the frequencies supplied to the track rails, and 40 amplifying apparatus between said receiving circuit and said selectively responsive means.
11. In a system of signaling, a series of successive block sections, means for supplying 45 said block sections with current of one or another frequency for the control of signals, and means whereby the frequency supplied to each section determines the frequency supplied to the next section in 50 the rear.
12. A train control system comprising a section of track, means for selectively supplying electric power to said track at one or another frequency, a train on said track, 55 a circuit on said train receiving energy from said track, amplifying means in said circuit, and means selectively responsive to the frequency in said circuit to control apparatus on the train.
- 60 13. A train control system comprising a section of track, a plurality of line wires supplied with energy of different frequencies, a plurality of transformers bridged across said line wires, means for selectively 65 energizing said track from one or another
- of said transformers, a train on said track, a circuit on said train receiving energy from said track, and means selectively responsive to the frequency in said circuit to control apparatus on the train. 70
14. Railway traffic controlling apparatus comprising a trackway divided into sections, means for each section for supplying alternating current to the rails thereof of one frequency or another, a vehicle, vehicle carried means controlled by energy received from the track rails and selectively responsive to currents of the several frequencies supplied to the rails, and vehicle governing apparatus controlled by 75 said vehicle carried means and requiring the control of said vehicle carried means by current in the track rails to allow the vehicle to proceed at maximum speed.
15. Railway traffic controlling apparatus comprising a section of track, means for supplying signaling current to the rails thereof of one frequency or another, vehicle carried means controlled by energy received from the track rails and selectively 80 responsive to currents of said different frequencies, and vehicle governing apparatus controlled by said vehicle carried means and requiring control of the vehicle carried means by current of a certain frequency 85 in the track rails to allow the vehicle to proceed at maximum speed.
16. Railway traffic controlling apparatus comprising track rails, a vehicle, means on the vehicle for permitting the vehicle to 90 proceed at maximum speed and other means on the vehicle for permitting the vehicle to proceed at restricted speed, apparatus on the vehicle controlled by energy received from the track rails and selectively responsive to current of one frequency or another for rendering one or the other of said vehicle-carried means effective, and means for supplying current of one of said frequencies 95 or the other to the track rails. 100
17. The method of controlling traffic, which consists in producing an alternating disturbance along a trackway carrying traffic to be controlled, governing the frequency of said disturbance by traffic conditions in advance, producing by said disturbance an altering electromotive force in a vehicle to be controlled, influencing thereby a local source of energy to produce energy changes of a corresponding relative frequency to the disturbances and greater than could be directly derived from the disturbance, and causing said local energy changes to selectively actuate traffic controlling means. 115
18. The method of controlling traffic, which consists in producing an electrical disturbance of one or another frequency in accordance with the degree of control desired, along a trackway carrying traffic to be con- 120

trolled, producing by said disturbance a corresponding electrical disturbance in a vehicle to be controlled, influencing thereby a local source of energy to produce energy 5 changes of a corresponding relative frequency to the disturbances and greater than could be directly derived from the disturbance, and causing said local energy changes to selectively actuate traffic controlling 10 means.

19. The method of controlling traffic, which consists in producing an alternating disturbance along a trackway carrying traffic to be controlled, governing the frequency 15 of said disturbance by traffic conditions in advance, producing by said disturbance an alternating electromotive force of corresponding frequency in a vehicle to be controlled, controlling thereby a local source 20 of direct current to produce an alternating current of a corresponding relative frequency, but regeneratively amplified, and actuating traffic controlling means on said vehicle by, and in accordance with the frequency 25 of, said amplified current to control the train in accordance with traffic conditions in advance.

20. Railway traffic controlling apparatus comprising a trackway divided into block 30 sections and a vehicle for travel thereon, a circuit on said vehicle, a plurality of sources of alternating current of different frequencies associated with each track section, means associated with each track section and controlled by traffic conditions in advance for selectively impressing one of said frequencies to the track section for creating an alternating electromotive force of corresponding frequency in said vehicle carried circuit, a 35 second circuit on said vehicle including a local source of current, amplifying means controlled by the alternating electromotive force in said first circuit for causing variations in the current in said second circuit of a corresponding relative frequency, and vehicle governing means controlled by the frequency of the current variations in the second circuit.

21. Railway traffic controlling apparatus 40 comprising a trackway and a vehicle for travel thereon, a circuit on said vehicle, means for impressing upon the trackway an alternating electromotive force of one or another predetermined frequency whereby a corresponding frequency is induced in said circuit, a second circuit on said vehicle including a source of current, amplifying means on the vehicle responsive to the induced frequency in said first circuit for causing variations in the flow of current in the second circuit of a corresponding relative frequency, and vehicle governing means controlled by the frequency of the variations in the current in said second circuit.

22. A railway system embodying means 65 for producing a clearance current for unlimited speed, and a different current for limited speed, means biased to retard the train and thrown out of operation by said clearance current, and means for producing a limited speed responsive to said limited speed current.

23. A railway signaling system comprising 70 a plurality of track sections, a relay for each section receiving energy from the rails of the section and comprising a member rotatable at two different speeds according as the relay is energized by alternating current of one frequency or another, said relay also comprising a plurality of contacts one or another of which is closed according as said member rotates at one speed or the other, means controlled by the relay of each section for supplying current of one of said frequencies or the other to the rails of the section in the rear, and signals for the sections controlled by the said relay contacts.

24. A railway signaling system comprising 75 a plurality of track sections, a relay for each section comprising a motor receiving energy from the rails of the section and rotatable at one speed or another according as it is energized by alternating current of one frequency or another, each relay also comprising a speed responsive device operated 80 by the motor and a plurality of contacts one or another of which is closed according as the speed responsive device is operated at one speed or the other, means controlled by the relay of each section for supplying current of one of said frequencies or the other to the rails of the section in the rear, and signals for the sections controlled by the 85 said relay contacts.

25. A signaling system comprising a plurality of track sections, a relay for each section comprising a motor receiving energy from the track rails of the section and operable at different speeds according as it is energized by current of one frequency or 90 another, means controlled by the relay of each section for supplying current of one of said frequencies to the rails of the section in the rear when the relay is de-energized and for supplying current of the other 95 said frequency to said rails when the relay is energized by current of either frequency, and a signal controlled by each relay and indicating "stop" when the motor is de-energized, "caution" when the motor operates at one of said speeds, and "proceed" 100 when the motor operates at the other speed.

26. A signaling system comprising a plurality of track sections, a relay for each section comprising a motor receiving energy from the track rails of the section and rotatable at different speeds according to the frequency of the current by which it is ener- 105 110 115 120 125

- gized, each relay also comprising a centrifuge, operated by the motor, means controlled by the relay of each section for supplying current of one frequency or another 5 to the rails of the section in the rear and a signal controlled by each relay and indicating "stop" when the centrifuge is at rest, "caution" when the centrifuge operates at one speed, and "proceed" when the centrifuge operates at another speed.
27. Railway traffic controlling apparatus comprising a series of track sections, means for each section for connecting a source of alternating current of one frequency or another 10 across the rails of the section at the exit end of the section according to traffic conditions in advance of the section, and train carried governing apparatus controlled by energy received from the track rails and including means selectively responsive to the frequency of the energy in said rails.
28. Railway traffic controlling apparatus comprising a series of track sections, means for each section for connecting a source of alternating current of one frequency or another 15 across the rails of the section at the exit end of the section according to traffic conditions in advance of the section, a circuit on a train receiving voltage from the track rails by induction, governing means 20 on the train controlled by the voltage induced in said circuit and including means selectively responsive to currents of the frequencies supplied to the track rails.
